(57) **CLAIM**

The ornamental design for a door with frame, as shown and described.

DESCRIPTION

FIG. 1 is a front, left side, top perspective view;

FIG. 2 is a front elevation view;

FIG. 3 is a rear elevation view;

FIG. 4 is a right side view (left side being a mirror image);

FIG. 5 is a top plan view;

FIG. 6 is a bottom plan view; and,

FIG. 7 is a front, left side, top perspective view with door in an alternate position.

The phantom representation of the hinges shown is made in the drawings merely for the purpose of illustrating the environment in which this invention is used. The structure shown in broken lines is not part of the design sought to be patented.
